UNITED STATES PATENT OFFICE.

CEFERINO GORCHS, OF BARCELONA, SPAIN.

DESIGN FOR A FONT OF TYPE.

SPECIFICATION forming part of Design No. 19,524, dated December 24, 1889.

Application filed September 13, 1889, Serial No. 323,871. Term of patent 3½ years. Registered in Spain April 14, 1887, No. 6,743; in France October 4, 1887, No. 7,625; in Austria-Hungary April 27, 1888, No. 5,910, and in Italy May 15, 1888, No. 182.

To all whom it may concern:

Be it known that I, CEFERINO GORCHS, a citizen of the United States of America, residing at Barcelona, in the Province of Catalonia and Kingdom of Spain, have invented a certain new and useful Design for a Font of Type for Spanish Script Alphabet, (which has been registered in France on the 4th day of October, 1887, No. 7,625; registered in Spain on the 14th day of April, 1887, No. 6,743; registered in Italy on the 15th of May, 1888, No. 182, and registered in Austria-Hungary on the 27th of April, 1888, No. 5,910,) of which the following is a specification, reference being had therein to the accompanying drawing.

My invention relates to designs for fonts of type; and it consists in the peculiar formation and curvature of script letters and figures.

The accompanying illustration represents the characteristics of such design, as shown in capitals, small letters, figures, and words made up of letters having the peculiarity of my design displayed.

The essential feature of my design is the peculiarity of the curves, which are made short and are heavily shaded and are drawn abruptly to a fine line. The characters are provided with an ornamental curl, of which this curve forms a part. This curl begins at the upper part of the letters and is extended downward and turned inward toward the letter, the heavy curve above described forming the bend of the curl at the lower end.

Having thus described my invention, what I claim, and desire to secure by Letters Patent, is—

A design for a font of type, consisting of characters having ornamental curls curved inward at their lower ends and heavily shaded at the bend, as set forth.

In testimony whereof I affix my signature in presence of two witnesses.

CEFERINO GORCHS.
